United States Patent Office

Des. 207,924
Patented June 13, 1967.

207,924

FLACON

Jacques Revillon, Paris, France, assignor to Parfums Revillon, Paris, France

Filed June 16, 1966, Ser. No. 2,706

Term of patent 14 years

(Cl. D58—8)

I claim:

The ornamental design for a flacon, as shown.
